[57] CLAIM

The ornamental design for a flashlight, as shown and described.

DESCRIPTION

FIG. 1 is a side elevational view of a flashlight embodying my design, the view from the opposite side being a mirror image thereof;

FIG. 2 is an end elevational view as seen from the left of FIG. 1;

FIG. b 3 is an end elevational view as seen from the right of FIG. 1;

FIG. 4 is a top plan view of the flashlight shown in FIG. 1; and

FIG. 5 is a bottom plan view thereof.
